FLUORESCENT LAMP SWITCH

George B. Horn, Fairfield, and Howard E. Youngs, Norwalk, Conn., assignors to The Wheeler Insulated Wire Company, Inc., Bridgeport, Conn., a corporation of Delaware

Application August 18, 1947, Serial No. 769,220

11 Claims. (Cl. 200—5)

1

The present invention relates in general to lighting systems and more especially to an improved switch-unit for lighting systems employing fluorescent lamps.

An object of the invention is to provide a switch-unit of superior construction and utility.

A still further object of the invention is to provide a superior two-button switch-unit which is economical to manufacture and assemble, and which provides a positive "on" and "off" snap-action.

A still further object of the invention is to provide a two-button snap-action switch-unit for fluorescent lamps wherein relatively simple but positive means is provided for starting the lamp, and wherein the installation of the switch-unit in a lighting circuit is simplified.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a schematic side elevation of the switch-unit of this invention connected in the lighting circuit of a fluorescent lamp;

Fig. 2 is a vertical longitudinal section partly in side elevation of the switch-unit of this invention, the "off" position of the push buttons being shown by full lines and the "on" position by broken lines;

Fig. 3 is a horizontal sectional view on line 3—3 of Fig. 2;

Fig. 4 is an end elevation in section on line 4—4 of Fig. 2;

Fig. 5 is an end elevation in section on line 5—5 of Fig. 2;

Fig. 6 is an end elevation in section on line 6—6 of Fig. 2;

Fig. 7 is a perspective view of the switch-cover looking mainly at the underside thereof;

Fig. 8 is a perspective view of the base of the switch;

Fig. 9 is a perspective view of the rocker-member of the switch-means of the switch;

Fig. 10 is a perspective view of one of the push buttons of the switch-unit;

Fig. 11 is a perspective view of one of the springs of the rocker-member; and

Fig. 12 is a perspective view of one of the starting-contacts.

It may be explained briefly that certain types of fluorescent lamps comprise sealed gas-filled

5

2

glass tubes provided at their opposite ends with filaments which are connected across a pair of electrodes, the latter in turn being connected by external terminals to suitable leads of an operating-circuit which is adapted to provide an electrical potential between the filaments by virtue of which electrons are induced to flow from one end of the tube to the other, so as to energize the gas therein and illuminate the tube. Normally, however, the potential between the filaments is insufficient to initiate electron emission and hence an auxiliary starting-circuit is used to heat the respective filaments to incandescence. The two-button snap-action switch-unit of this invention is one which is adapted to close the starting- and operating-circuits of the tube substantially simultaneously but to keep the starting-circuit closed only momentarily, the latter being opened immediately after the tube lights.

10 Referring to the drawings, and in particular to Fig. 1, the latter shows the improved switch-unit, indicated schematically at 15, connected in the circuit of a fluorescent tube 16 which is provided at its opposite ends with filaments 17 and 18 respectively connected across electrodes 19, 20 and 21, 22 respectively, which in turn are provided with external terminals 23, 24 and 25, 26. The corresponding leads of the terminals 24 and 26, hereinafter identified by similar reference 15 numbers, constitute part of the starting-circuit of the switch-unit and are adapted to be connected to suitable starting-contacts, hereinafter described, of its starting-button 27. The corresponding leads of the terminals 23 and 25 are 20 connected across the line L through operating-contacts, hereinafter described, of the "on" and "off" or operating-button 28 of the switch-unit, the lead 25 having a choke-coil or ballast 29 in series to provide an induced voltage for lighting the tube in the manner well known to the art.

25 The improved switch-unit 15 is shown in detail in Figs. 2 through 12 and comprises a substantially-rectangular body consisting of a cover-portion 30 and base-portion 31. In the preferred 30 construction, both the cover and base are molded or otherwise formed from plastic material having insulating properties. The cover 30 is a substantially-rectangular inverted U-shaped member comprising a top 32 and spaced-parallel side walls 33 depending substantially perpendicularly therefrom. The opposite ends of the cover are partially closed by integral depending end walls 34, the lower edges 35 of which are provided with substantially-rectangular notches 36. The latter are formed on the inside faces of the respective

35

end walls 34 and are adapted, as hereinafter described, to provide means for assembling the base 31 to the cover 30. The top 32 of the cover is provided with two integral upstanding molded collars 37, the inner annular walls of which are coextensive with a pair of cylindrical apertures 38 formed in the top of the cover, the centers of the apertures 38 being on the longitudinal axis of the cover and, in the present embodiment, are spaced apart longitudinally from each other a distance substantially equal to the distance measured from the center of each respective aperture to its respective end of the cover. The coextensive annular walls of the apertures 38 and their respective collars 37 constitute guide-means for the upper ends of the push buttons 27 and 28, as hereinafter described. A third cylindrical aperture 39 is formed on the longitudinal axis of the cover between the two guide-apertures 38 to receive an assembly-screw 40 which may be used both to mount the switch-unit on a light-harness or other supporting-means and to positively secure the cover to the base, as described below. Referring particularly to Figs. 2 and 7, the aperture 39 is provided with a concentric collar 41 which is molded or otherwise formed on the underside of the top 32 of the cover and projects downwardly substantially perpendicularly thereto. Formed also on the underside of the cover-top 32 and at diametrically-opposite points of the concentric collar 41 are web-members 42 which extend transversely of the cover, each web being substantially wedge-shaped in cross section so as to provide a knife edge or fulcrum 43 for the purpose hereinafter described.

Turning again to the side walls 33 of the cover, the lower portions thereof are made somewhat thicker than the upper portions, as indicated clearly in Figs. 4, 5 and 6, so as to provide an outwardly-flared skirt 44 at the lower edge of each side, each skirt being provided on its inside wall with a longitudinal clearance-groove 45, the upper edge of which comprises a longitudinal shoulder 450, and the lower edge of which intersects the bottom edge of its respective side wall. Each longitudinal clearance-groove 45 is provided, moreover, with a plurality of substantially-rectangular recesses 46 which extend longitudinally thereof and are adapted to cooperate with suitable locking-elements of the base, as hereinafter described, to detachably secure the base to the cover. In the present embodiment, three locking-recesses 46 are shown, one recess at opposite ends respectively of each side wall and one recess intermediate the end recesses. It will be understood, however, that more than three recesses may be provided, or that a single recess extending throughout the length of the clearance-groove would be equally effective.

Referring particularly to Fig. 8, the base 31 comprises a substantially-rectangular bottom 47, the longitudinal edges of which are provided with a plurality of outwardly-projecting lugs 48 corresponding in number and location to the number and location of the recesses 46 in the clearance-grooves of the cover. The lugs 48 constitute locking-elements for detachably securing the base to the cover and to this end are adapted to snap into the recesses 46 of the latter, as the bottom 47 of the base 31 is pushed up between the lower edges thereof. To this end, the distance measured between the outer faces of each pair of oppositely-disposed lugs is greater than the distance between the longitudinal clearance-grooves 45 of the cover (see Fig. 5),

as a consequence of which the outwardly-projecting lugs 48 of the base-bottom 47 force the skirts 44 of the side walls outwardly as the base is pushed up into the cover, until the lugs 48 engage in the respective recesses 46 thereof, whereupon the skirts and, in particular, the lower edges of the cover snap back and tightly grip the longitudinal sides of the bottom 47 of the base, the longitudinal upper edges thereof abutting the shoulders 450 of the cover and the underside of the bottom 47 being substantially flush with the lower edges of the cover. In accordance with this construction, the base is securely but detachably fastened to the cover, thereby effecting an economy in assembly costs.

As shown in Figs. 2 and 8, each end of the base 31 is provided with an integral upstanding end wall 49 which is made substantially equal in width and height to the opening in the corresponding end of the cover so as to effectively close the latter when the base is assembled therein, as shown in Fig. 6. Moreover, the upper edge of each end wall 49 of the base is shown provided on its inner edge with an upstanding substantially-rectangular tongue 50 which is adapted to seat in the corresponding notch 35 in the lower edge 35 of the end wall 34 of the cover, so as to prevent the base from moving longitudinally relative thereto.

Referring more especially to Figs. 2 and 8, the bottom 47 of the base is provided intermediate its opposite ends with an upstanding substantially-cylindrical center-post 51 having a longitudinal axial aperture 52 which intersects the underside of the base-bottom 47 and which is provided with internal screw threads. The internally-threaded aperture 52 of the center-post 51 is adapted to be in axial alignment with the assembly-screw aperture 39 of the cover when the latter is assembled on the base, so as to receive the lower threaded end of the assembly-screw 40, whereby the cover and base may be positively held together. It will be appreciated, too, that by providing an assembly-screw of sufficient length, the lower end thereof may project below the bottom of the switch so as to provide means for attaching the switch to a light-harness or other supporting-means.

Formed integrally on diametrically-opposite sides of the post are a pair of external ribs 53, each of which extends longitudinally of the post and substantially perpendicularly to the bottom 47 of the base, the upper edge of each rib constituting a relatively-short transverse knife edge or fulcrum 54. As shown in Fig. 2, each fulcrum 54 of the base is adapted to be located substantially opposite and in vertically-spaced relationship to the corresponding fulcrum 43 of the cover when the latter is assembled on the base.

Formed in the bottom 47 of the base between its center-post 51 and the corresponding end walls 49 are two pairs of transverse, relatively-shallow grooves 55 and 56 respectively. Each groove is substantially U-shaped in cross section and each pair of grooves 55 and 56 respectively is separated by a transverse partition or wall 57 and 58, the partition 58 being substantially half the height of the partition 57, in order to provide clearance for the contact-arm of the starting-contact members which are adapted to be assembled in the grooves 56, as hereinafter described. The pair of grooves 55 differ from the pair of grooves 56 in that each groove 55 is provided at one end with a substantially-rectangular shallow relief-recess 59 which intersects the corresponding edge

of the base and is adapted to provide clearance for the operating-contact members of the grooves 55, as set forth below. The opposite ends of the grooves 55 and the corresponding ends of the grooves 56 are provided with apertures 60 and 61 respectively which in the present embodiment are adapted to receive the leads of the terminals 24, 25 and 26 of the lamp 16 and the lead "L" of the line "L," each of these leads being arranged to be soldered or otherwise secured to the underside of one of the contact-members of the pair of contact-members 62 and 63 respectively mounted in the corresponding pairs of grooves 55 and 56 of the base. It is within the purview of the invention, however, to connect each contact-member to its respective lead by extending a terminal-portion of each contact-member through the apertures 60 and 61 of its respective groove to the underside of the base and to secure the leads to these extended terminal ends of the conductors by detachable fastening-means.

The two pairs of contact-members hereinafter referred to as the operating contact-members 62 and the starting contact-members 63 respectively, constitute elements of the switch-means and, in general, comprise relatively-thin substantially-rectangular sheet-metal members (see Fig. 3), each having its longitudinal edges bent downwardly and outwardly so as to make a tight fit in its respective groove of the base and to support the main body of the contact-member slightly above the bottom of the groove a distance corresponding to the depth thereof, as shown in Fig. 2. Further, each contact-member is substantially equal in length to the width of the base so that when the cover is assembled thereon, the longitudinal shoulders 450 of its opposite lower edges will engage the opposite outer ends respectively of each contact-member to hold it firmly in its respective groove in the base.

The operating-contacts 62 of the grooves 55 are preferably formed of sheet copper, although any other suitable metal may be used, and are identical in shape, each having a terminal-arm 64 formed integrally at the end thereof opposite that to which its respective lead is connected, the terminal-arm projecting upwardly substantially perpendicularly and having an elbow 65 at its upper end, as shown especially well in Fig. 6, whereby the terminal end 66 of each arm is displaced inwardly from the adjacent side of the cover. Moreover, the operating-contact member 62 nearest the center-post 51 is provided with an aperture 67 intermediate its opposite ends and in axial alignment with an aperture 68 in the bottom 47 of the base, the aperture 68 being in axial alignment with one of the cylindrical guide-apertures 38 in the top of the cover, whereby the two apertures 38 and 68 constitute guide-means for the operating push button 23 of the switch, as hereinafter described. Since the contact-members 62 are made identical for effecting economies of mass production, the other contact-member 62 has a central aperture also, but this particular aperture serves no useful purpose in the assembly.

The starting-contact members 63 are preferably silver although aluminum, copper or other similar metal may be used. The outer of the two starting-contact members 63 comprises a rectangular plate with down-turned edges, as described above, whereas the starting-contact member 63 nearest the center-post 51 is provided with an integral spring-arm 69 which extends transversely thereof and is bent back upon itself, as

indicated clearly in Figs. 2 and 12, to provide a contact-arm 70 adapted to extend across the partition or wall 58 of the base, the outer free end 71 of the contact-arm 70 being bent downwardly and located immediately above and normally in vertically-spaced relationship to the outer starting-contact member 63. The inner starting-contact member 63 is provided with an aperture 72 intermediate its opposite ends and in axial alignment with a guide-aperture 73 in the bottom of the base, the guide-aperture 73 being in axial alignment with the corresponding guide-aperture 38 of the cover to form guide-means for the starting push button 27 of the switch-unit, as herein-after described. A suitable slot 74 is provided in the contact-arm 70 of the contact-member 63 in alignment with the apertures 72 and 73 respectively to permit the push button 27 to extend therethrough, as indicated in Figs. 2 and 4.

It is customary in lighting switches of this type to provide a condenser in parallel with the lamp in order to suppress radio interference. In the present embodiment, a condenser 75 of substantially 0.004 microfarad capacity is adapted to be mounted on the bottom of the base adjacent one end wall 49 thereof, the longitudinal axis of the condenser extending transversely of the base. The two leads 76 and 77 of the condenser are shown soldered or otherwise secured to the respective starting-contact members 63 so as to make good electrical contact therewith.

An additional element of the switch-means is a rocker-member which, as indicated at 78, comprises a substantially-rectangular frame (see Fig. 9) made of sheet brass or other suitable metal having longitudinal sides 79 provided with downwardly-bent flanges 80, and ends 81 provided with downwardly-bent flanges 82, the sides and ends of the frame defining a longitudinal substantially-rectangular aperture therein. One longitudinal side 79 is also provided with an integral contact-arm 83 which constitutes an extension of its respective flange 80, the contact-arm 83 being adapted to engage the terminal-arms 64 of the contacts 62, as hereinafter described. The inner edge of each side 79 of the rocker-member is provided with a pair of substantially-rectangular notches 84 which are spaced apart longitudinally, the notches in one side being substantially opposite the notches in the other side of the frame. The notches 84 of the frame are adapted to provide clearance for the keys of the push buttons, whereby the latter may be inserted into the longitudinal aperture of the rocker-member and keyed therein, as hereinafter described.

The rocker-member 78 is adapted to be mounted in the switch-unit so as to oscillate therein and to this end the transverse distance between the inner edges of the longitudinal sides 79 of the frame corresponds to or is slightly greater than the diameter of the center-post 51 of the base, whereby the longitudinal sides 79 of the frame are adapted to engage on the transverse fulcrums 54 thereof, as shown in Figs. 2 and 5. Moreover, when the cover is assembled on the base, the transverse fulcrums 43 thereof make engagement with the upper surfaces of the longitudinal sides 79 of the frame, as a consequence of which the latter is pivotally supported for oscillating movement in the switch-unit but held positively from either lateral or vertical displacement.

In order to provide the push buttons 27 and 28 of the switch-unit with a positive snap action, 75 suitable resilient-means are associated with the

rocker-member to resiliently hold the latter at each extreme of its oscillating movement. Referring to Figs. 2 and 11, the resilient-means of the rocker-member comprises a pair of leaf-springs 85, each of which is bowed and provided at one end with a tongue 86 and at its opposite end with a split tongue 87 having transversely-extending barbs. Each spring-member 85 is adapted to be attached to one end respectively of the rocker-member by engaging the split tongue 87 in a transverse slot 88 formed in the flange 82 at the end of the rocker-member, the barbs of the split tongue being adapted to engage on the inside of the end flange 82 to effectively lock the resilient-member 85 thereto. Referring to Fig. 2, it will be noted that the spring 85 of the right-hand end of the rocker-member is arranged so as to bow downwardly, whereas the spring 85 at the left-hand end of the rocker-member is arranged to bow upwardly. This particular arrangement of the respective springs is preferred since by assembling the upwardly-bowed spring at the left-hand end of the switch, enough clearance space is secured to accommodate the condenser-coil 75 which, as pointed out above, is shunted across the starting-contact members 63. The outer end of each spring 85 and more especially the tongue-portion 86 thereof, is adapted to be secured in the corresponding notch 36 of the cover-member between the upper end of the tongue 50 of the end wall 49 and the upper shoulder of the notch 36. In accordance with this construction, both springs are under maximum stress when the rocker-member is in a substantially-horizontal position and, hence, each spring effectively resists displacement of the rocker-member from either extreme of its oscillatory movement, i. e., the rocker-member is resiliently held at either extreme of its oscillating movement and moves from one extreme to the other with a positive snap-action. The springs 85 also serve to prevent the rocker-member from moving longitudinally on its fulcrums by engagement of the shoulders of the split tongues 87 with the respective end-flanges 82 of the rocker-member.

The rocker-member 78 is adapted to be operated manually by the starting and operating push buttons 27 and 28 respectively, each push button being substantially identical except that the starting-button 27 is usually red in color and the operating-button 28 black, so as to readily distinguish the functions thereof. Each button comprises a substantially-cylindrical head-portion 89 which is adapted to make a smooth sliding fit in its respective collared guide-aperture in the top of the cover, the length of each cylindrical head-portion of the push button being substantially equal to one-half its overall length. The lower half of each push button comprises a shank-portion 90 immediately beneath the cylindrical head-portion, the shank 90 being substantially square in cross section and equal in width to the transverse distance between the opposite longitudinal edges of the rocker-member, whereby one pair of diametrically-opposite sides 91 of the shank-portion of each push button is adapted to make a relatively-close sliding fit in the longitudinal aperture of the rocker-member. Moreover, each side 91 of the shank 90 is provided with a key or rib 92 which extends upwardly longitudinally and symmetrically of each side 91 from the bottom thereof up to the shoulder 93 formed at the intersection of the upper end of the shank and the lower end

5 of the cylindrical head-portion 89 of the button. The distance between the outer faces of the respective ribs 92 of each button exceeds the width of the longitudinal aperture in the rocker-member but is substantially equal to the distance between the oppositely-disposed notches 84 of the rocker-member. Consequently, each push button may be inserted into the longitudinal aperture of the rocker-member only by engaging its ribs 92 10 in the oppositely-disposed notches 84 thereof. Further, each longitudinal rib is adapted to be divided into an upper and lower rib respectively by means of a transverse slot 920, the width of the slots in the ribs of the operating-button 28 15 being no more than twice the thickness of a side 79 of the rocker-member, whereas the width of each slot in the ribs of the starting-button 27 is more nearly four times the thickness of a side 79 of the rocker-member. The latter construction provides for a lost-motion connection between the rocker-member and the starting-button 27, as hereinafter described. By engaging the sides 79 20 of the rocker-member in the corresponding slots 920 of the push-button ribs, each push button is 25 permitted to move longitudinally in the longitudinal aperture of the rocker-member to a position adjacent one end thereof thereby displacing the ribs 92 out of alignment with the notches 84 in the sides 79 of the rocker-member. Consequently, the upper ends of the lower ribs are 30 located beneath the underside of the longitudinal sides 79 of the rocker-member, whereby each push button is effectively prevented from being drawn upwardly out of the rocker-member. On 35 the other hand, the lower end of each upper rib engages on the top of each side 79 of the rocker-member to provide contact therewith, whereby, by pushing downwardly on the respective push buttons, the rocker-member will be oscillated on 40 its fulcrums. Moreover, since the diametrically-opposite sides 91 of each push button makes a substantially-close fit in the longitudinal aperture of the rocker-member, the push buttons are effectively prevented from rotating therein.

45 Projecting downwardly from the shank-portion of each push button is a pilot 94 which comprises a cylindrical stem of relatively-small diameter adapted to make a close sliding fit in the corresponding guide-apertures 68 and 73 respectively in the bottom 47 of the switch-unit, thereby 50 to guide the lower ends of the respective push buttons and to prevent the push buttons from moving longitudinally in the aperture of the rocker-member.

55 The elements of the switch-unit are adapted to be assembled as follows: the leads 25, "l," and 24, 60 26 are soldered to the corresponding pairs of contact-members 62 and 63 after which the latter are assembled in their respective grooves 55 and 56 in the base of the switch by passing the leads down through the corresponding apertures 60 and 61 therein. The condenser is then mounted at one end of the base and shunted across the starting-contacts 63. The rocker-member, including the springs 85 secured at opposite ends thereof and the push buttons 27 and 28 engaged in its longitudinal aperture, is mounted on the fulcrums of the center-post 51 and held while the push buttons are moved outwardly to the outer ends 65 of the rocker-member so as to engage the pilot-stems 93 at the lower ends of the push buttons in the guide-apertures in the base of the switch. The tongues at the outer ends of the springs 85 70 are then engaged on the upper edges of the lugs 50 of the end walls, whereupon the cover is slipped

down over the assembly. The upper cylindrical head-portions of the push buttons are thereby projected up through the guide-apertures of the cover and as the locking-lugs of the base snap into the recesses in the lower edges of the cover to lock the cover and base together, the tongues of the springs are simultaneously pinched between the upper edges of the respective lugs 50 and the shoulders of the recesses of the cover, while the fulcrums of the latter engage on the upper surfaces of the oscillatable rocker-member to hold it down firmly on the fulcrums of the center-post. Although the coaction of the lugs of the base and the recesses in the cover serves admirably to detachably secure the cover to the base, it is desirable to positively hold the two elements together by the assembly screw 40 which is inserted into the hole in the cover and threadedly engaged at its lower end in the internally-threaded aperture of the center-post.

The operation of the switch-unit may be described briefly as follows. Assuming the leads of the starting push button 27 and the leads of the operating push button 28 are connected in the lamp circuit, as indicated in Fig. 1, then when the operating-button 28 is in its lowermost position, as indicated in Fig. 2, the lamp will be "off," since the rocker-member has been oscillated clockwise thereby moving its contact-arm 83 below the terminal-arms of the operating-contact members 62, as indicated in Fig. 6. To light the lamp, the operator pushes the starting-button 27 downwardly to oscillate the rocker-member in a counterclockwise direction, indicated by the broken lines in Fig. 2, thereby elevating the contact-arm 83 of the rocker-member into engagement with the upper ends 66 of the terminal-arms of the operating-contacts 62. Simultaneously, as the starting-button 27 is pushed down, the lower end of its substantially-rectangular shank is adapted to engage the contact-arm 70 of the starting-contacts 63 at the left-hand end of the switch-unit, so as to depress the outer free end 71 of the contact-arm into engagement with the outer starting-contact members 63 thus closing the circuit between the two starting-contact members 63. Consequently, the circuit is completed from the filaments 17 and 18 at opposite ends of the lamp 16 to the line L, whereupon the filaments are heated to incandescence so as to effect an emission of electrons and energize the gas in the lamp to illuminate the latter. As soon as the tube is illuminated, the operator releases the starting-button 27 and the resiliency of the contact-arm lifts up the starting-button slightly, which action is permitted by the lost-motion connection between the starting-button 27 and rocker-member, as hereinabove described, and breaks the connection between the two starting-contacts 63 so as to cut off the flow of current to the filaments of the tube. The contact-arm 83 of the rocker-member remains, however, in engagement within the upper ends 66 of the terminal-arms of the operating-contact members 62 and, hence, the line potential is maintained between the filaments of the lamp to continue the flow of electrons between opposite ends thereof. Since the time required to heat the filaments to incandescence is ordinarily a matter of but a fraction of a second, the operator holds down the starting-button 27 only long enough to momentarily close the starting-contacts 63. In order to put the light out, the operator simply presses down the operating-button 28 so as to oscillate the rocker-member clockwise and dis-

engage its contact-arm from the terminal-arms of the operating-contact members 62, thereby opening the circuit to the filaments of the lamp.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. A switch-unit comprising a body of insulating material; switch-means mounted in said body of insulating material comprising a pair of contacts adjacent opposite ends respectively of said body and a rocker-member supported intermediate its opposite ends in said body so as to oscillate into and out of engagement with one pair of contacts; and separate manually-operated members mounted in said body and arranged to engage said rocker-member at opposite ends thereof respectively so as to oscillate said rocker-member thereby to alternately close and open said one pair of contacts, one of said separate members having a lost-motion connection with said rocker-member and arranged both to actuate said member to close said one pair of contacts and simultaneously to close the second pair of contacts and by its lost-motion connection with said member to open said second pair of contacts without opening the said one pair of contacts.
2. A switch-unit comprising a body of insulating material; switch-means mounted in said body of insulating material comprising a pair of contacts at one end of said body and a second pair of contacts including a resilient contact-arm at the opposite end of said body, a fulcrum in said body, and a rocker-member mounted on said fulcrum intermediate its opposite ends so as to oscillate into and out of engagement with one pair of contacts at opposite extremes respectively of its movement; and separate manually-operated members mounted in said body and arranged to engage said rocker-member at opposite ends thereof respectively to oscillate said rocker-member thereby to alternately close and open said one pair of contacts, one of said separate members being arranged also to engage the resilient contact-arm of said second pair of contacts to close the second pair of contacts substantially simultaneously with the closing of said one pair of contacts, said resilient contact-arm being arranged to automatically open said second pair of contacts on release of said one separate member.
3. A switch-unit comprising a body of insulating material; switch-means mounted in said body of insulating material comprising a pair of contacts adjacent opposite ends respectively of said body, a fulcrum in said body, a rocker-member mounted on said fulcrum intermediate its opposite ends so as to oscillate into and out of engagement with one pair of contacts at opposite extremes respectively of its movement, and an over-center spring secured at each end of said rocker-member substantially in alignment with the longitudinal axis thereof to resiliently hold said rocker-member at the opposite extremes of its movement; and separate manually-operated members mounted in said body and arranged to engage said rocker-member at opposite ends thereof respectively to oscillate said rocker-member thereby to alternately close and open said one

pair of contacts, one of said separate members being arranged also to momentarily close the second pair of contacts.

4. A switch-unit comprising a body of insulating material; switch-means mounted in said body of insulating material comprising a pair of contacts adjacent opposite ends respectively of said body and a longitudinally-slotted rocker-member supported intermediate its opposite ends in said body so as to oscillate into and out of engagement with one pair of contacts at opposite extremes respectively of its movement; and a pair of push buttons mounted in said body, each push button being constructed and arranged to make non-rotatable engagement in the longitudinal slot of said rocker-member adjacent opposite ends thereof respectively, and each push button having a transverse shoulder arranged to engage on said rocker-member so as to oscillate said rocker-member thereby to alternately close and open said one pair of contacts, one of said push buttons being arranged also to momentarily close the second pair of contacts.

5. A switch-unit comprising a body of insulating material; switch-means mounted in said body of insulating material comprising a pair of contacts adjacent opposite ends respectively of said body and a longitudinally-slotted rocker-member supported intermediate its opposite ends in said body so as to oscillate into and out of engagement with one pair of contacts at opposite extremes respectively of its movement; and a pair of push buttons mounted in said body, each push button comprising a substantially-rectangular shank-portion arranged to make nonrotatable engagement in the longitudinal slot of said rocker-member, an enlarged head at the upper end of said shank and a depending pilot at the lower end of said shank, said head and pilot of each respective push button being arranged to slide in axially-aligned apertures in the top and bottom respectively of said body to guide the push button, said enlarged head-portion of each push button being adapted to form a transverse shoulder arranged to engage on said rocker-member adjacent opposite ends thereof respectively so as to oscillate said rocker-member thereby to alternately close and open one pair of contacts, one of said push buttons being arranged also to momentarily close the second pair of contacts.

6. A switch-unit comprising a body of insulating material; switch-means mounted in said body of insulating material comprising a pair of contacts adjacent opposite ends respectively of said body and a longitudinally-slotted rocker-member supported intermediate its opposite ends in said body so as to oscillate into and out of engagement with one pair of contacts at opposite extremes respectively of its movement; and a pair of push buttons mounted in said body, each push button comprising a shank-portion having at least two diametrically-opposite flat sides arranged to engage in the longitudinal slot of said rocker-member to prevent rotation of said push buttons therein, and each push button having a transverse shoulder above said shank-portion arranged to engage on said rocker-member adjacent opposite ends thereof respectively so as to oscillate said rocker-member thereby to alternately close and open said one pair of contacts, one of said push buttons being arranged also to momentarily close the second pair of contacts.

7. A switch-unit comprising a body of insulating material; switch-means mounted in said body

of insulating material comprising a pair of contacts adjacent opposite ends respectively of said body and a longitudinally-slotted rocker-member supported intermediate its opposite ends in said body so as to oscillate into and out of engagement with one pair of contacts at opposite extremes respectively of its movement; and a pair of push buttons mounted in said body, each push button comprising a shank-portion having at least two diametrically-opposite flat sides arranged to engage in the longitudinal slot of said rocker-member to prevent rotation of said push buttons therein, laterally-projecting ears on the shank of each push button, said ears being arranged to engage the underside of the longitudinal edges of the slot in said rocker-member to prevent said push button from moving upwardly therein, and shoulders projecting transversely from the shank-portion of each push button and arranged to engage on the top side of the longitudinal edges of said slot to prevent said push buttons from moving downwardly therein, said push buttons being arranged to engage opposite ends of said rocker-member so as to oscillate said rocker-member thereby to alternately close and open said one pair of contacts, one of said push buttons being arranged also to momentarily close the second pair of contacts.

8. A switch-body comprising a body-portion having a base-portion and a separate cover-portion, each consisting of an insulating material; a protuberance projecting upwardly from said base-portion intermediate the opposite ends thereof and provided with laterally-projecting knife-edges; a protuberance projecting downwardly from said cover-portion intermediate the opposite ends thereof and provided with laterally-projecting knife-edges, said cover-portion being arranged to be detachably assembled on said base-portion whereby the respective knife-edges of said cover and said base constitute upper and lower fulcrums in vertically-spaced relationship; switching-means mounted in said base-portion comprising a pair of contacts adjacent opposite ends respectively of said base and a rocker-member comprising a longitudinally-slotted substantially-rectangular plate, said rocker-member being arranged to be oscillatingly supported intermediate its opposite ends between said upper and lower fulcrums and adapted at one extreme of its oscillating movement to close one pair of contacts; and a pair of push buttons mounted in said cover-portion, said push buttons being arranged to engage in the slot of said rocker-member adjacent opposite ends thereof to oscillate said member thereby to alternately close and open said one pair of contacts, one of said push buttons being arranged also to momentarily close the second pair of contacts.

9. A switch-body comprising a body-portion having a base-portion and a separate cover-portion, each consisting of an insulating material; a post projecting upwardly from said base-portion intermediate the opposite ends thereof and provided with laterally-projecting knife-edges; a collar projecting downwardly from said cover-portion intermediate the opposite ends thereof and provided with laterally-projecting knife-edges, said cover-portion being arranged to be detachably assembled on said base-portion whereby the respective knife-edges of said cover and said base constitute upper and lower fulcrums in vertically-spaced relationship; switching-means mounted in said base-portion comprising a pair of contacts adjacent opposite ends respectively of

said base and a rocker-member comprising a longitudinally-slotted substantially-rectangular plate, said rocker-member being arranged to be oscillatingly supported intermediate its opposite ends between said upper and lower fulcrums and adapted at one extreme of its oscillating movement to close one pair of contacts; a pair of push buttons mounted in said cover-portion, said push buttons being arranged to engage in the slot of said rocker-member adjacent opposite ends thereof to oscillate said member thereby to alternately close and open said one pair of contacts, one of said push buttons being arranged also to momentarily close the second pair of contacts; and resilient means supported at opposite ends of said cover and arranged to engage corresponding ends of said rocker-member to resiliently hold said rocker-member at opposite extremities of its oscillating motion.

10. A switch-body comprising a body-portion having a base-portion and a separate cover-portion, each consisting of an insulating material; a post projecting upwardly from said base-portion intermediate the opposite ends thereof and provided with laterally-projecting knife-edges; a collar projecting downwardly from said cover-portion intermediate the opposite ends thereof and provided with laterally-projecting knife-edges, said cover-portion being arranged to be detachably assembled on said base-portion whereby the respective knife-edges of said cover and said base constitute upper and lower fulcrums in vertically-spaced relationship; switching-means mounted in said body comprising a pair of contacts mounted in said base at opposite ends thereof respectively, and a rocker-member comprising a longitudinally-slotted substantially-rectangular plate, said rocker-member being arranged to be oscillatingly supported intermediate its opposite ends between said upper and lower fulcrums and adapted at one extreme of its oscillating movement to close one pair of contacts; a pair of push buttons mounted in said cover-portion, said push buttons being arranged to engage in the slot of said rocker-member adjacent opposite ends thereof to oscillate said member thereby to alternately close and open said one pair of contacts, one of said push buttons being arranged to momentarily close the second pair of contacts, resilient-means mounted in said cover at opposite ends thereof, said resilient-means being arranged to engage corresponding ends of said rocker-member to resiliently hold said rocker-member at opposite extremities of oscillating motion; and a condenser mounted at one end of said cover within the enclosure of the resilient-means at the corresponding end thereof and transversely to the longitudinal axis of said body, said condenser being connected to the adjacent pair of contacts.

11. A switch-body comprising a body-portion having a base and a separate cover, each consisting of an insulating material; a protuberance projecting upwardly from said base intermediate the opposite ends thereof and provided with laterally-projecting knife-edges; a protuberance projecting downwardly from said cover intermediate the opposite ends thereof and provided with laterally-projecting knife-edges, said cover being arranged to be detachably assembled on said base whereby the respective knife edges of said cover and said base constitute upper and lower fulcrums in vertically-spaced relationship; switching-means mounted in said base-portion comprising a pair of contacts adjacent opposite ends respectively of said base, one pair of contacts having a resilient contact-closing arm arranged normally in spaced relationship to its respective contacts, and a rocker-member comprising a longitudinally-slotted substantially-rectangular plate having a contact-closing arm at one end, said rocker-member being arranged to be oscillatingly supported intermediate its opposite ends between said upper and lower fulcrums and adapted at one extreme of its oscillating movement to engage its contact-closing arm with the said second pair of contacts; a pair of push buttons mounted in said cover, said push buttons having substantially-rectangular shank-portions arranged to engage in the slot of said rocker-member to prevent rotation of said push buttons therein; push-button guide-means in said cover and said base; and a transverse shoulder on each push button arranged to engage on said rocker-member adjacent opposite ends thereof to oscillate said member thereby to alternately close and open said second pair of contacts, one of said push buttons being arranged to engage the contact-closing arm of the said first pair of contacts to momentarily close the latter as the contact arm of said rocker-member is moved into contact with said second pair of contacts.

GEORGE B. HORN.
HOWARD E. YOUNGS.
